UNITED STATES PATENT OFFICE.

HERMAN L. KUTTER, OF HAMILTON, OHIO, ASSIGNOR TO THE BLACK-CLAWSON COMPANY, OF HAMILTON, OHIO, A CORPORATION OF OHIO.

PAPER-MAKING MACHINE.

Application filed December 26, 1923. Serial No. 682,684.

This invention relates to paper making machinery and more particularly to an improved Fourdrinier construction.

One of the principal objects of the invention is to provide an improved type of shaking Fourdrinier machine.

Another object of the invention is to provide apparatus of this character which is so constructed that changing the wire may be readily and easily accomplished.

Another object of the invention is to provide in an improved Fourdrinier a shaking forming section which is adapted for bodily movement out of alignment with the remainder of the paper-making apparatus, to effect replacement of the wire, or for similar purposes; and in which the breast roll, save-alls, and the like are carried by the forming section, when that section is subjected to such bodily movement.

Another object of the invention is to provide an improved form of supporting mechanism for the shaking section of a Fourdrinier machine which is constructed for substantially frictionless shaking motion.

Another object of the invention is to provide a shaking section in a Fourdrinier machine, in which the save-alls are carried by the shaking section, but are restrained against shaking motion, as that section is shaken.

Still another object of the invention is to provide a shaking section of a Fourdrinier machine, which is so constructed that definite positioning of the save-alls relative to the rolls is assured.

Other objects and advantages of the invention will be apparent from the description thereof set out below, when taken in connection with the accompanying drawing.

In the drawing, in which like characters of reference designate like parts throughout the several views thereof,

Fig. 1 is a side elevation of the forming section of a paper making machine constructed in accordance with this invention;

Fig. 2 is a similar view, with some of the parts omitted for purposes of simplifying the drawing, showing the forming section in elevated position, preparatory to moving it out of alignment with the remainder of the paper-making apparatus;

Fig. 3 is an enlarged elevational view of the breast roll end of the forming section showing more in detail the features of construction;

Fig. 4 is a sectional view along the line 4—4 of Fig. 1, looking in the direction of the arrows;

Fig. 5 is an end elevational view, looking from the right of Fig. 1;

Fig. 6 is a detail view, partly in section, of one of the roller carriages on which the forming section is moved bodily;

Fig. 7 is a vertical sectional view along the line 7—7 of Fig. 8 with certain parts shown in elevation to more clearly disclose the invention;

Fig. 8 is a sectional view through the shaking support, along the line 8—8 of Fig. 7;

Fig. 9 is a detail sectional view along the line 9—9 of Fig. 8; and

Fig. 10 is a detail sectional view showing the mounting of the breast roll doctor.

As is well known, one of the most troublesome features in the operation of paper-making machines of the Fourdrinier type is the changing of the wire. In the ordinary form of apparatus this is accomplished by removing all of the table rolls, the various save-alls, the breast roll and other parts, in order to permit of placing the new wire in position. In the form of apparatus which is disclosed herein, and constituting a preferred embodiment of the invention, this changing of the wire is made a comparatively easy and simple job; for the forming section of the machine is so constructed that the breast roll

may be moved bodily from its normal operating position and suspended in temporary supports carried by the forming section to thus provide adequate slackening of the wire, after which the entire forming section, together with the breast roll, table rolls, save-alls, and such other parts as are associated with it, may be moved bodily out of alignment with, and completely to one side of,

the remainder of the paper-making machine, and so from inside the wire, so that replacing of the wire may be readily accomplished, after which the Fourdrinier part, along with its associated parts, is moved back into its proper operating position, within the new wire, the breast roll is then returned to its

75

80

85

90

95

100

proper operating position, the various other parts properly positioned, and the device is then ready for operation.

As shown in the drawing, that part of the machine which is associated with the pulp feed box, from which the pulp is fed to the breast roll, is designated generally by the numeral 15, this part of the apparatus being fixed, and having the breast roll end of the 5 shaking or forming section associated therewith, the other end of this section being associated with a fixed part of the frame which is designated generally by the numeral 16, this part also being stationary. For purposes of convenience in description, this shaking part of the Fourdrinier is herein referred to as the "forming section," because the actual forming of the sheet of paper is largely completed while the wire passes 10 through the extent of this shaking part. The forming section comprises a truss at each side, the upper rail 20 of which serves as a shaking side rail. At the couch roll end the forming section is provided at each side, 15 with a heel pivot which in this case consists of a readily removable pin 22, extending through a suitable hole in the shaking side rail into a socket in the fixed part of the frame; the forming section during operation 20 oscillating in a substantially horizontal plane about the heel pivots. The truss member may be of any desired construction, but preferably each truss member consists of the two end members 23 and 24, which are connected at their lower ends by means of beams 25, suitable struts 26 being positioned between the side rails 20 and the beams 25 to strengthen and add rigidity to the truss construction. Mounted upon the machine are 25 the usual deckle straps 27 which travel through wash troughs 28, and around the pulley 29, these parts being of conventional construction.

Associated with each side of the forming section, at the breast roll end, is a supporting and shaking member which is designated generally by the numeral 35, each of these shaking supports receiving at its upper end, as shown most clearly in Fig. 3, a housing 36, which, as shown clearly in Fig. 2, is in the nature of a jaw member, adapted to receive the bearing retaining sleeve 37. Within this bearing sleeve is mounted a ball bearing which receives the end of the shaft of the breast roll. A cap 38 is removably held in place within the jaw member 36 by means of bolts 39, this cap serving to retain the bearing sleeve in position within the housing 36, to thus hold the breast roll in operating position. In each bearing a suitable end thrust receiving member 40 is provided. These members not only take up end thrust, but by adjustment wear may be taken up so that the undesirable shaking due to end play of 60 the breast roll will be avoided. By remov-

ing the bolts 39 the cap 38 may be withdrawn and the breast roll with its bearings removed as a unit, the relative adjustment of the roll shaft in the bearings being thus undisturbed. These bearings are preferably provided with end shields 41 which prevent the flow of water thereinto.

It is not essential that ball bearings be used, but suitable roller bearings or even conventional solid bearings may be used if desired. Roller bearings of course, should be retained within a bearing sleeve as described above so that the breast roll and the two bearings may be moved as a unit and without disturbing the adjustment of these parts. This jaw member 36 is adapted to receive, in pivotal connection, the breast roll end of each of the shaking side rails 20, each of these rails being connected to one of the jaw members by means of a pin 42, which extends through an opening in the rail and is threadedly mounted within a pivoted member 43 carried within a suitable socket in the jaw member. One of these shaking supports as shown in Fig. 5, is provided with a socket member 44, which is adapted to receive one end of a shake bar 45, the other end of this bar being connected to any suitable mechanism for causing up and down motion of that end of the bar. Preferably this bar has attached to one end an extensible link 46 which in turn is connected to a movable crank pin carried by the shaking apparatus (not shown). This construction allows of easy alignment of the breast roll frame. As the end of the bar is given up and down motion, it will transmit oscillating motion to the shaking support to which it is attached, those members being in turn so constructed that they will rock to cause substantially horizontal shaking of the breast roll end of the forming section.

As shown most clearly in Fig. 7, each of these shaking supports comprises a channeled frame member 50, which is adapted to receive the lift bar 51. These two supports are of similar construction except that only one has a socket for receiving the shake bar 45 and therefore only one need be described in detail. The frame member is provided at its lower end with outwardly extending trunnion members 52, each of which is adapted to rest upon the upper face of a base member 53, which is in turn rigidly fixed to the foundation in any suitable manner. This base member is provided with an opening 54 through which extends the lower end of the frame 50, and the lower end of the lift bar 51. Each of the two base members has an upward extension 55 to which are connected the opposite ends of a beam 56, which holds the parts in fixed relationship. Each of the base members 53 is also provided at each side of the opening 54 with upwardly extending, and overturned, flanges

57, which cooperate with the trunnion extensions 52, and retain those extensions in definite position. During operation lubricant is placed within the pocket formed by the flanges 57 and a plate 58 is positioned within the opening 54, at each side thereof, to prevent the escape of the lubricant. Also a plate 59 is positioned at each end of flanges 57 to prevent escape of lubricant. The lower face of each of the trunnion extensions 52 is curved. Each lift bar 51, at its upper end, is provided with lateral extensions 60, the upper faces of the lift bars and of these lateral extensions being curved, the curvature thereof corresponding to, and being of the same radius as the curvature of the lower faces of the trunnion extensions 52. In other words, as indicated by the dotted line A in Fig. 7, the bearing faces of the trunnion extensions 52 and of the upper end of the lift bar 51 and its lateral extensions, are curved planes lying within the surface of a given cylinder. Each of the trunnion extensions 52 is provided upon each side face with a facing member 61, which is rigidly secured thereto, and the outer face of which is curved. Positioned within the retaining flanges 57, and cooperating with each of the facing members 61, is a complementary gib or strip 62, the cooperating faces of these strips 62 being curved to correspond to the curvature of the outer faces of the members 61. If desired suitable strips, in the nature of shims, may be used to back up the strips 62. As shown one of these strips 63 is of steel and the other 64 of leather. This is preferred for the leather serves to absorb some of the shock arising during rocking; but any suitable material may be used for these shims. The construction is such that when thus assembled the flanges 57 overlie the facing members 61 and gibs 62 to retain the frame 50 in position with respect to the base 53 and since this base member is fixed, any rocking of the lift bar and frame, through the medium of the bar 45 will necessarily cause those parts to rock about the trunnion extensions 52, which are restrained against bodily movement, by the parts just described. The upper end of the lift bar, and its lateral extensions 60, has mounted thereon a cap 65, which supports and has connected thereto against sliding motion, the jaw member 36. This cap member is preferably integral with the jaw member 36. This cap is provided with downwardly extending and overturned flanges 66, within which are positioned strips 67, similar in form and function to the strips 62 heretofore described, which are also backed up by suitable shims 68. The upper end of each lift bar and its extensions are provided with facing strips 69, which are similar in form and function to the strips 61 described above. As the bar 45 is moved it will cause the casing 50, with the parts connected thereto, to rock about the trunnion extensions 52. And since the upper ends of the lift bars 51 are connected to the side shake rails, through the medium of the jaw member 36 and the pins 42, an oscillating motion will be imparted to the breast roll end of the forming section, as is the usual practice. But inasmuch as the lower face of the trunnion extensions 52 and the upper face of the lift bar 51 and its lateral extensions 60, have the same curvature a substantially frictionless motion will result since the trunnion extensions 52 will roll upon the cooperating faces of the bases 53 and the upper curved faces of the lift bars and the lateral extensions thereof will roll upon the cooperating face of the cap 65. Consequently a true rolling motion results, which is practically free from friction. Furthermore as a result of this construction the cap 65 will move in a substantially horizontal plane, with no up and down motion, as is inevitable with the usual type of support which is pivoted at its lower end to some fixed part of the foundation, and is also pivoted at its upper end to the shaking frame. The curvature of the cooperating faces of the members 61 and 62 and members 67 and 69 is such that as the casing 50, and the lift bar therein, are subjected to this above described rolling motion these cooperating faces will slide freely one upon the other, this construction being analogous to that present in a well constructed ball and socket joint. The members 61-62, 67-69 take up any end thrust that is present during operation of the device, and also provide means whereby wear may be compensated for. Threadedly mounted within the flanges 57 are the adjusting screws 63', through manipulation of which the shims 63 may be moved to compensate for wear. Each of the caps 65 is also provided with similar adjusting screws 68'. Plates 59' and 69' are provided for preventing the escape of lubricant from about the upper end of the lift bars. One of the great defects present in shaking sections as heretofore used has been the difficulty of securing adequate lubrication of the surfaces of the shaking supports. Consequently wear has been comparatively rapid, although the movements of these parts are slow. And in fact it has been this slow movement which gave rise to the difficulty of obtaining adequate lubrication. But with the construction shown herein the surfaces which sustain the weight of the parts have a rolling motion relative to each other and wear is therefore practically negligible. However these parts are surrounded by lubricant during operation as the cooperative faces of the members 61-62, 67-69 have sliding motion relative to each other and lubrication is needed. As is obvious from the drawing the construction of these sup-

porting members is such that they pump oil in between the faces of these cooperating parts during rocking of the supports and adequate lubrication is thus secured even though the parts move so slowly.

Each of the lift bars 51 is provided in one face with rack teeth 70. The channeled frame 50 is provided with a cover 71. Mounted in this cover is a shaft 72, which is provided within its length with an enlargement having teeth thereon, thus constituting a pinion 73, the teeth of which mesh with the teeth 70 upon the cooperating lift bar. Also mounted within each cover 71 is a second shaft 74 which is arranged parallel to the shaft 72. Connected to the cover 71 is a gear case 75, provided with suitable openings to receive the respective ends of the shafts 72 and 74, the end of each shaft extending through these openings into the gear case. Suitably connected to the gear case is a gear case cover 76. Mounted upon the outer end of the shaft 72 is a gear 77, which meshes with a corresponding gear 78, which is mounted upon the shaft 74 intermediate its length. Also mounted upon the shaft 74 is a worm gear 79, which meshes with a worm pinion 80 mounted upon the shaft 81, the outer end of which has a sprocket wheel 82 pinned thereto. This sprocket wheel receives a chain 83 which also runs over a second sprocket wheel 84, mounted upon the shaft 85. This shaft is supported at its opposite ends, in suitable bearings which are mounted in the standards 86, and carries thereon two of the smaller sprocket wheels 84, one adjacent each end, which wheels cooperate respectively with the two sprocket wheels 82, there being one of these sprocket wheels 82 associated with each shaking support. At one end the shaft 85 is provided with a hand wheel 87, which is so positioned that it may be readily manipulated by an operator. Upon movement of the hand wheel to cause rotation of the shaft 85, the gear members associated with the two lift bars will be actuated to cause up and down movement of those lift bars to raise or lower the breast roll end of the forming section as desired. And by properly proportioning the gears, sprocket wheels, etc., the two lift bars may be caused to move in unison, to raise or lower each side of the shaking part the same amount.

This type of shaking part as is the general practice, is provided with the usual table rolls 90, and with save-alls. It is quite desirable, and is the usual practice, that the save-alls which are associated with shaking parts shall be maintained stationary during operation. This is ordinarily accomplished by mounting the save-alls upon supports which are entirely separate from the frame of the shaking part, being secured to the foundation of the machine. As shown in the draw-

ing the save-alls, in this invention, are supported by the frame of the shaking part itself.

Two save-alls are shown, a first save-all 100 and a second save-all 101; but of course any desired number of save-alls may be used. The first save-all is supported at one side by the upper edge of the second save-all, which in turn is supported by the frame of the shaking part. The other, or front, side of the first save-all has an I-beam 102 rigidly attached thereto, to which is connected at each end a bracket 103, having a roller 104 therein. Carried by each of the front members 24 is a forwardly extending bracket 105, each of which has a stub shaft 106 mounted therein, and positioned to receive the rollers 104 to support the front side of the first save-all. The second save-all is provided, upon each side thereof with an angle iron 107, which is of more rigid material than the body of the save-all and serves as a track to ride upon the flanged rollers 108, each of which is mounted upon a bracket 109, which is in turn rigidly secured to the frame of the shaking part. Each of the save-alls is thus supported by the frame of the shaking part, but is movable relative thereto, within a given range. In order to maintain each of the save-alls stationary while the forming part is being shaken during operation, each of these save-alls is connected to a stationary standard, which holds the save-all against movement so that the frame of the shaking part will move back and forth under the save-alls which ride upon the rollers, free movement of the save-alls and frame of the shaking part relative to each other being thus permitted. The standard 110, which is associated with the first save-all and the standard 111 which is associated with the second save-all are substantially identical in construction. The construction of these standards is clearly shown in Figs. 1 through 4. Each of these standards has a slot or groove 112 therein, through which a retaining bar 113 extends, the inner end of this bar being cut away as shown at 114 for positioning within a grooved bracket carried by the respective save-alls. The grooved bracket associated with the first save-all 100 is clearly shown in Fig. 4 and is designated by the numeral 115, this bracket being preferably carried by the bracket in which the roller is mounted. The bracket 110 which is associated with the second save-all 101 is clearly shown in Fig. 1, for example, and is designated by the numeral 116, this bracket being preferably mounted directly upon the save-all itself, or upon the track 107. Secured upon each of the retaining bars is a collar 117 which is positioned for contacting with the inner face of the standard, when the bar is in assembled position. The outer end of the retaining bar is

threaded to receive a hand wheel 118, which cooperates with one end of a coil spring 119 surrounding the end of the bar, the other end of the spring contacting with a ⁵ slideable collar 120 which is pressed by the spring against the standard to clamp the standard between the two collars. By proper manipulation of the hand wheel the tension of the spring may be varied so that the retaining ¹⁰ bar may be moved to, and held in, any desired vertical positioning within the slot in the standard. Due to this construction the save-alls are held relatively stationary as the forming section is given its shaking ¹⁵ motion, the shaking part running back and forth under the save-alls which are restrained against movement by means of the bar. When desired the retaining bars may be manipulated to remove the cut away ends ²⁰ from the grooves in the brackets so that the save-alls may be then moved with the forming section.

This first save-all is closely associated with the breast roll, and the breast roll doctor is preferably mounted therein. This doctor consists of a metal plate 125 which is faced with a wearing plate 126. At each end this plate 125 is rounded to ride in a corresponding groove in a bearing member ²⁵ 127, which is riveted to the save-all. Also at each end the plate 125 has an upstanding extension to which is bolted a lever 128 which extends beyond the front end of the save-all and has a weight 129 hung thereon. By ³⁰ means of this construction the breast roll doctor is at all times urged by the weight to swing upon the bearings 127 to hold the plate 126 snugly against the surface of the breast roll. Proper positioning of the ³⁵ breast roll doctor relative to the breast roll is thus at all times secured. And because of the pivotal mounting which is used, the breast roll doctor may be readily lifted, bodily out of the save-all when this becomes ⁴⁰ desirable.

Carried by the frame of the shaking section, at each side thereof and adjacent the opposite ends of the first save-all, are two tracks 131. Connected to each end of the ⁴⁵ first save-all is a hanger 132 which has a roller 133 mounted thereon which rollers are mounted for cooperation with these tracks. Because of its considerable length the first save-all is cumbersome and unwieldy ⁵⁰ and this track and roller mounting facilitates handling thereof. For the tracks 131 sustain the weight of this save-all through the medium of the hangers and rollers so that it may be readily handled in moving it ⁵⁵ from operative position back into the second save-all which is the inoperative position.

As stated above, it is necessary to change the wire in a machine of this character every few weeks, and this constitutes a laborious ⁶⁰ and difficult task; but in the device shown

herein this task is very greatly simplified, for means is provided whereby the forming section, with a number of its associated parts, is moved bodily out of the way so that the changing of the wire may be readily accomplished. ⁷⁰

During operation the side shake rails are pivotally connected to and supported at the couch roll end by the frame 16; and are pivotally connected and supported at the ⁷⁵ breast roll end by the shaking support 35, through the medium of the jaw member 36.

Positioned at each side of the Fourdrinier part and adjacent the ends of the beams 25 are track supporting standards 150, each of ⁸⁰ which has two inverted V-shaped upright extensions 151 (which are adapted to receive a V-shaped track member 152. Pivots mounted upon the beams 25 at each end thereof are roller bearing frames 153. As ⁸⁵ shown there are two frames at each end of each beam, one on the inside and one on the outside of the beam, each of them being provided with an extension 154, which is pivotally positioned within a passage 155 in the ⁹⁰ enlargement 156 of the beam the extensions 154 being in alignment when positioned within this passage 155. These two frames are held within the passage 155 by means of a bolt 157, which holds them against separation, and therefore holds them in place. Each of these frames is provided with two rollers 158, one at each end thereof, which are adapted to cooperate with the tracks 152, as shown in Fig. 2. The tracks 152 are used ⁹⁵ only when the forming section is being moved into, or out of, alignment with the remainder of the machine, and they are not in position when the machine is completely assembled ready for operation, as shown in ¹⁰⁰ Fig. 1. When it is desired to move the forming section out of alignment with the remainder of the machine it is first lifted upwardly. The breast roll end is lifted by proper manipulation of the lift bar, the ¹⁰⁵ couch roll end being raised by means of a screw jack 160, which is supported by a suitable bracket attached to the frame 16. When the forming section has been raised sufficiently, to substantially the position in ¹¹⁰ Fig. 2 for example, the breast roll doctor is lifted from its bearings and laid down in the pan of the save-all, the first save-all is then lifted and slid back into the second, deep, save-all 101, as shown in Fig. 2. The caps ¹¹⁵ 38 are then removed from the breast roll, with its bearings, picked up bodily by means of a crane or in some other suitable manner, and hung on the brackets 105. This of course causes slackening of the wire, a supporting bar, which is not shown in the drawing, being temporarily positioned in place to hold the wire while the forming section is being moved out of, and back into, place. V-shaped bars 165, having rollers 166 mounted ¹²⁰

¹²⁵ and 130

therein, are then placed in position upon the standards 150, these bars being supported at their ends in V-shaped grooves 167, which are provided in the inner ends of the extensions 151. These bars have to support comparatively little weight and are therefore made light so that they can be easily handled without the danger of damage to the wire. The bars 165 having been placed in position the heavier tracks 152, which are adapted to support the entire weight of the forming section are then placed in position by being run over the rollers 166, manipulation of these heavy tracks being thus facilitated. Two temporary standards 170, shown in Fig. 4 are then placed to receive sections of track 171, which are similar to the tracks 152, and one end of each of which is supported by the fixed standard 150, the standard 170 being so positioned that the tracks 171 will be in alignment with the tracks 152. The shaking support 35 and the screw jack 160 are then lowered until the rollers 158 rest upon the tracks 152, after which the shaking support 35 and the screw jack are still further lowered so that the forming section is entirely free from these two parts, being supported entirely upon the tracks 152.

30 The forming section or shaking part may now be moved bodily out of alignment with the remainder of the machine, and completely from within the wire which is hanging loose.

35 The old wire having been removed and the new wire placed in position, this part is then rolled back along the tracks 171 and 152 until it is in alignment with the remainder of the machine. The shaking support 35 and the screw jack 160 are then elevated to again pick up the forming section. This having been done the breast roll is then moved from its temporary supports back into the jaw member 36, where it is clamped into position.

40 The first save-all is then moved out of the second save-all and placed in position and the breast roll doctor replaced therein. And since the breast roll doctor is mounted in a definite position within this first save-all, the screw jack 160 are then lowered to again pick up the forming section. This having been done the breast roll is then moved from its temporary supports back into the jaw member 36, where it is clamped into position.

45 The first save-all is then moved out of the second save-all and placed in position and the breast roll doctor replaced therein. And since the breast roll doctor is mounted in a definite position within this first save-all, 50 and both the breast roll and this first save-all have a definite mounting upon the forming section relative to each other, the breast roll doctor will automatically assume proper positioning relative to the breast roll. The tracks 171 are now removed, together with the standards 170. The tracks 152 are then removed by being rolled along the rollers 166; after which the bars 165 carrying the rollers 166 are slid out of position. The 55 shaking support 35 and the screw jack 160 are then lowered to bring the forming section into the proper position relative to the rest of the apparatus. Of course such other incidental parts as were necessarily removed 60 during these manipulations are replaced at

the proper time so that the device will be entirely assembled. The parts having been thus reassembled the bars for retaining the save-alls against shaking are replaced and the device is then ready for operation. 70

While the form of apparatus herein described constitutes a preferred embodiment of the invention, it is to be understood that the invention is not limited to this precise form of apparatus, and that changes may be 75 made therein without departing from the scope of the invention which is defined in the appended claims.

What is claimed is:

1. In a paper-making machine of the character described, a shaking forming section, a supporting shaking standard, a curved load-receiving surface upon said standard, a co-operating sustaining surface upon said shaking forming section, means for acting upon the said standard to effect shaking of the forming section, the said surfaces being so cooperatively constructed as to effect substantially rolling motion with respect to each other during shaking of the forming section, 90 and means for controlling bodily movement of the forming section with respect to the said standard.

2. In a paper-making machine of the Fourdrinier type, a shaking forming section, an extensible supporting standard therefor, and means for moving said forming section bodily out of alignment with the remainder of the machine.

3. In a paper-making machine, of the Fourdrinier type, a shaking forming section, extensible standards for supporting said section constructed for rocking motion to shake the said forming section and means for moving said section bodily from its supporting 100 means and completely out of alignment with the remainder of the machine.

4. In a paper-making machine of the Fourdrinier type, a forming section, rollers carried by said forming section, a standard 110 for supporting said section, constructed for rocking motion to shake the forming section; means for actuating said supporting standard to raise the forming section bodily; and removable tracks adapted for positioning 115 while the forming section is in elevated position and to receive the rollers upon the forming section when said section is at a certain elevation, the construction being such that the forming section may be rolled along the tracks and moved bodily out of alignment with the remainder of the machine.

5. In a paper-making machine of the Fourdrinier type, a forming section, supporting rollers mounted upon said section, a shaking standard for supporting said forming section and constructed for imparting shaking motion thereto, means for actuating said supporting standard to raise or lower the said forming section, track receiving stand- 130

ards, adapted to receive removable tracks while said section is in elevated position, the standards being so positioned that when the tracks are supported thereby they will 5 receive the rollers upon the forming section as the supporting means therefor is lowered, the construction being such that the forming section may be moved bodily out of alignment with the remainder of the machine.

10 6. In a paper-making machine of the Fourdrinier type, a forming section constructed for bodily movement out of alignment with the remainder of the machine, pivoted frames mounted upon said forming 15 section and supporting rollers carried by said frames constructed for receiving a track upon which the said forming section is moved bodily.

7. In a paper-making machine of the Fourdrinier type, a shaking forming section, comprising a truss frame having a bottom beam at each side of the forming section, a carriage pivotally mounted upon each side of each truss beam at each end of such beam, 25 each such carriage being centrally pivoted, a supporting roller at each end of each carriage, track supports positioned adjacent the ends of the truss beams, means carried by each support for receiving two removable 30 tracks, the positioning of the track supports being such that the tracks carried thereby will receive the said supporting rollers, and means for raising the said forming section to permit of positioning the tracks in place, 35 and for lowering the said forming section to bring the said supporting rollers upon the tracks to support the said forming section, whereby the said forming section may be moved bodily out of alignment with the remainder 40 of the machine.

8. In a paper-making machine of the Fourdrinier type, a shaking forming section comprising a frame, an extensible supporting standard therefor, having correspondingly curved surfaces at the top and bottom thereof and means for causing substantially frictionless rocking of said supporting means to cause shaking of the forming section in a substantially horizontal 45 plane, and means for extending said standard irrespective of the bearing relationships at the opposite ends thereof.

9. In a paper-making machine of the Fourdrinier type, a shaking forming section comprising a frame; an extensible supporting standard for said forming section, the upper end of which cooperates with said frame and the lower end of which rests upon a flat base plate a curved surface at the 55 upper end of said supporting means in rolling contact with said frame, a curved surface at the lower end of said supporting means in rolling contact with a plane surface on the flat base plate, and means for 60 rocking said supporting means about its 65

lower end, the curvature of the upper and lower surfaces being such that substantially frictionless rolling motion of the curved surface at the upper end of the supporting means upon the cooperative portion of the 70 frame and substantially frictionless rolling motion of the curved surface at the lower end of the supporting means upon the sustaining base plate will result.

10. In a paper-making machine of the 75 character described, a shaking forming section, an extensible supporting means therefor, a sustaining base plate, a substantially frictionless rocking connection between the lower end of the said supporting means and 80 the base plate, and a substantially frictionless rocking connection between the upper end of the supporting means and the said forming section.

11. In a paper-making machine of the 85 character described, a forming section, an extensible means for supporting said forming section, means associated therewith for shaking said forming section back and forth, the construction being such that the back 90 and forth motion of the forming section takes place in a substantially horizontal plane.

12. In a paper-making machine, the combination with a shaking forming section, of 95 a supporting means comprising a lift bar having a curved upper face adapted to receive the forming section in rolling contact, a housing for said lift bar, outward extensions thereon having curved lower faces, a 100 base member supporting said outward extensions in rolling contact, the curved face at the upper end of the lift bar and the curved faces of the outward extensions on the housing being of the same radius, and 105 means for rocking said housing about the curved faces of its outward extensions, whereby shaking motion is imparted to the forming section, the upper and lower curved 110 faces moving upon the forming section and base plate respectively with a substantially frictionless rolling motion.

13. In a paper-making machine, the combination with a forming section, of a supporting means comprising a lift bar having 115 a curved upper face adapted to receive the forming section in rolling contact, a housing for said lift bar, outward extensions thereon having curved lower faces, a base member supporting said outward extensions in rolling contact, the curved face at the upper end of the lift bar and the curved faces of the outward extensions on the housing being of the same radius, means for rocking said 120 housing about the curved faces of its outward extensions, whereby shaking motion is imparted to the forming section, the upper and lower curved faces moving upon the forming section and base plate respectively 125 with a substantially frictionless rolling mo- 130

tion, and means associated with the outward extensions on the said housing for taking up thrust and wear.

14. In a paper-making machine of the character described, a shaking forming section, a supporting shaking standard having a curved load-receiving surface at the upper end thereof, a cooperating sustaining surface upon said shaking forming section, a curved bearing surface at the lower end of said standard, a supporting base member having a bearing surface cooperating with the lower curved surface on the supporting standard, means for effecting movement of this supporting standard to cause shaking of the forming section, the cooperating bearing surfaces at the upper and lower ends of the standard being respectively constructed to effect substantially rolling motion as between each pair of cooperating surfaces, and adjustable means for controlling bodily movement of the forming section with respect to the said standard.

15. In a paper-making machine, a shaking forming section, an extensible supporting standard for the breast roll end of said forming section, and track receiving standards associated with said forming section, removable tracks for positioning upon said track receiving standards, roll bearing carriages on the forming section for cooperation with the said removable tracks, the construction being such that the shaking forming section may be moved bodily out of alignment with the remainder of the machine.

16. In a paper-making machine, a forming section, an extensible supporting means therefor, and track receiving standards associated therewith and constructed to receive removable tracks, rollers on the forming section for cooperating with the said tracks whereby the said forming section may be moved bodily out of alignment with the remainder of the machine and means at each end of said forming section for raising and lowering the said part.

17. In a paper-making machine, a shaking forming section, an extensible shaking support for the breast roll end of said section, extensible supporting standards at the couch roll end thereof, and track receiving standards for receiving assembled tracks associated with said forming section, supporting rollers carried by said forming section for cooperating with the said tracks to move the forming section bodily out of alignment with the remainder of the machine, the supporting means at each end of said forming section being constructed for raising and lowering said forming section.

18. In a paper-making machine, a shaking forming section, save-alls mounted on said forming section, means for holding the save-alls stationary while the said forming section is shaking, said means being detachable

from the save-alls to permit movement of the save-alls with the forming section as that section is moved bodily.

19. In a paper-making machine, a shaking forming section, save-alls mounted on said shaking forming section, and means for holding the said save-alls stationary as the forming section shakes.

20. In a paper-making machine, a forming section, means for shaking said forming section, tracks carried by said forming section, save-alls associated with said forming section, rollers on said save-alls cooperating with the said tracks, and means for holding the said save-alls against movement as the forming section is shaken.

21. In a paper-making machine, a shaking forming section, save-alls carried by said forming section, said forming section and save-alls being provided with tracks and rollers, so that the save-alls and the forming section are movable relative to each other, and means for holding said save-alls against movement as the forming section is shaken.

22. In a paper-making machine, a shaking forming section, save-alls mounted upon said forming section and movable relative thereto, stationary standards positioned adjacent the forming section, retainer rods mounted in said standards, and detachable means connecting the said retainer rods to the save-alls to hold the said save-alls stationary while the forming section shakes.

23. In a paper-making machine, a shaking forming section, save-alls carried by said forming section and movably relative thereto, means for shaking said forming section in a substantially horizontal plane, and means for holding said save-alls against movement as the forming section is thus shaken.

24. In a paper-making machine, a forming section, adjustable supports therefor constructed for rocking motion to shake said forming section, means for actuating the said supports to raise and lower the said forming section, tracks carried by the said forming section, a save-all associated with said forming section, rollers thereon cooperating with the said tracks to support the said save-all from the forming section, and means separate from the said forming section for restraining the said second save-all against movement as the forming section is shaken.

25. In a paper-making machine, a forming section, means for shaking the said forming section, a second save-all, rollers and tracks associated with said second save-all and said forming section for supporting said save-all in a relatively movable relation with respect to the said forming section, a first save-all, rollers and tracks associated with said first save-all and said forming section, for supporting the said first save-all in rela-

- tively movable relation with respect to the forming section, and means for restraining each of said save-alls against movement as the forming section is shaken.
- 5 26. In a paper-making machine, a forming section, means for shaking said forming section, a second save-all carried by said forming section and movable relative thereto, a first save-all carried by said forming section and movable relative thereto and partly supported by the said second save-all, and means for restraining the said save-alls against movement as the forming section shakes.
- 10 27. In a paper-making machine, a shaking forming section, a save-all carried by said forming section and movable relative thereto, and means for restraining said save-all against movement as the said forming section is shaken.
- 15 28. In a paper-making machine, a shaking forming section, a save-all carried by said forming section and movable relative thereto, detachable means for restraining said save-all against movement as the forming section is shaken, and means for moving said forming section, with the save-all carried thereby, bodily out of alignment with the remainder of the machine.
- 20 29. In a paper-making machine, a shaking forming section, means for shaking said forming section, a plurality of save-alls, co-operating rollers and tracks carried by said save-alls and said forming section for supporting said save-alls from the forming section, and means for restraining said save-alls against movement as the forming section shakes.
- 25 30. In a paper-making machine, a shaking forming section, means for shaking said forming section, a plurality of save-alls, co-operating rollers and tracks carried by said save-alls and said forming section for supporting said save-alls from the forming section, means for restraining said save-alls against movement as the forming section shakes and means for moving said forming section, with the save-alls carried thereby, out of alignment with the remainder of the machine.
- 30 31. In a paper-making machine, a shaking forming section, a save-all carried thereby and supported on rollers, and means for holding said save-all against movement as the forming section is shaken.
- 35 32. In a paper-making machine, a shaking forming section, a save-all carried thereby and supported on rollers, and fixed means, constructed for up and down movement, for holding said save-all against movement as the forming section is shaken.
- 40 33. In a paper-making machine, a forming section constructed to be moved bodily out of alignment with the remainder of the machine, a breast roll associated with said forming section and adapted for movement therewith in connection with the bodily movement of the said forming section, a save-all carried by said forming section and associated with said breast roll and mounted for movement out of operative association with said breast roll when the forming section is moved bodily, and means for assuring definite relative positioning of the said breast roll and save-all when the save-all is in its operative position.
- 45 34. In a paper-making machine, a shaking forming section, supports therefor, a breast roll carried by said supports, a breast roll doctor carried by said forming section and constructed for positioning to cooperate with the said breast roll, means for moving said breast roll doctor from its operative position when the forming section is moved bodily out of alignment with the remainder of the machine, the construction being such that definite positioning of the breast roll doctor relative to the breast roll is secured when the parts are returned to operating position.
- 50 35. In a paper-making machine, a forming section, a breast roll associated therewith, a breast roll doctor carried by the said forming section, means for moving the said breast roll and the said breast roll doctor out of operative position, as when it is desired to change the wire, the mounting for the said breast roll doctor and for the said breast roll being so relatively constructed that definite relative positioning of the breast roll and breast roll doctor will be assured when the parts are in operating position.
- 55 36. In a paper-making machine, a shaking forming section, means for moving said forming section bodily out of alignment with the remainder of the machine, means for supporting said forming section in operating position, a breast roll mounted upon said supporting means, a save-all carried by said forming section, means for holding said save-all against movement as the said forming section is shaken, a temporary breast roll support carried by said forming section, said save-all being constructed for movement upon said forming section to permit of positioning the said breast roll temporarily in said temporary support, the construction of the forming section, save-all and supporting means being such that definite relative positioning of the save-all and breast roll will be assured when the said parts are in operating position.
- 60 37. In a paper-making machine, a bodily removable forming section, comprising a removable breast roll, a movable save-all carried by said forming section and adapted to cooperate with said breast roll, and a breast roll doctor mounted within said save-all.
- 65 38. In a paper-making machine, a forming

section, a breast roll associated therewith, a save-all carried by said forming section, and a breast roll doctor pivotally mounted within said save-all.

5 39. In a paper-making machine, a forming section, a breast roll associated therewith, a save-all carried by said forming section, a breast roll doctor pivotally mounted within said save-all and means for causing movement of said breast roll doctor about its pivot into cooperative relation with the said breast roll.

10 40. In a paper-making machine comprising a forming section, and a breast roll associated therewith; a save-all, and a breast roll doctor pivotally mounted therein.

15 41. In a paper-making machine comprising a forming section, and a breast roll associated therewith; a save-all, and a breast roll doctor removably mounted therein.

20 42. In a paper-making machine comprising a forming section and a breast roll associated therewith; a save-all, constructed for positioning adjacent said breast roll, bearing blocks mounted within said save-all, a breast roll doctor, and pivot portions at the ends thereof constructed for positioning within the said bearing blocks.

25 43. In a paper-making machine, a shaking forming section adapted to be moved bodily out of alignment with the remainder of the machine, means for pivotally connecting one end of said forming section to a couch roll frame, means for supporting the breast roll end of said forming section and adapted for rocking motion to cause shaking of the said forming section, means associated with the said last named supporting means for actuating the said means in unison to cause 30 raising or lowering of the shaking end of the said forming section, and means associated with the couch roll end of the said forming section for raising or lowering that end of the said forming section.

35 44. In a paper-making machine, comprising a forming section adapted for bodily movement out of alignment with the remainder of the machine, a plurality of standards adapted to receive and support removable

40 tracks, means for supporting a light guide track, a bar having rollers thereon for positioning within said light guide track, and heavier tracks adapted to move upon said rollers for movement into position upon the said standards.

45 45. In a paper-making machine, a forming section adapted for bodily movement out of alignment with the remainder of the machine to permit of replacing the wire or the like, a breast roll associated with said forming section, table rolls carried by said forming section, a plurality of save-alls carried by said forming section and mounted for limited movement relative thereto, a breast roll doctor mounted within one of said save-alls,

means for restraining the said save-alls against movement as the forming section is shaken, said restraining means being detachable from the said save-alls to permit bodily movement of the save-alls with the forming section, the mounting of the save-alls upon the forming section being such that when the parts are in operating position definite positioning of the save-alls relative to the table rolls, and of the breast roll doctor relative to the breast roll, will be assured.

50 46. In a paper-making machine, a forming section adapted for bodily movement out of alignment with the remainder of the machine to permit of replacing the wire or the like, a breast roll associated with said forming section, table rolls carried by said forming section, a plurality of save-alls carried by said forming section and mounted for limited movement relative thereto, means for restraining the said save-alls against movement as the forming section is shaken, said restraining means being detachable from the said save-alls to permit bodily movement of the save-alls with the forming section, the mounting of the save-alls upon the forming section being such that when the parts are in operating position definite positioning of the save-alls relative to the table rolls will be assured.

55 47. In a paper-making machine, a shaking forming section, a rocking support therefor, a curved trunnion surface at its lower end, a plane surface base member for receiving said curved trunnion surface in rolling relation, convex side surfaces upon the lower end of said supporting member, complementary concave surfaces carried by the base member and cooperating with said convex surfaces, and means for rocking the said supporting means upon the said base member, the said base member being constructed to receive a supply of lubricant and the construction of the complementary convex and concave surfaces being such that during operation of the device lubricant will be caused to move between these surfaces to effect lubrication.

60 48. In a paper-making machine, a shaking forming section, a rocking support therefor, a housing associated with said forming section a curved surface at the upper end of said support constructed for substantially frictionless rolling engagement within the said housing to sustain the forming section, a base member having a pocket therein, a curved surface at the lower end of the said support constructed for substantially frictionless rolling engagement within the said base member pocket, convex side surfaces upon the upper and upon the lower ends of said support, and complementary concave members within the said housing and the base member pocket in sliding contact respectively with the convex surfaces of the

upper and lower ends of the support, and means for rocking the support upon the base member, the housing and the base member pocket being constructed to receive lubricant 5 and the construction of the cooperative parts at the upper and lower ends of the support respectively being such that during shaking of the forming section lubricant will be caused to move between the cooperative 10 concave and convex surfaces.

49. In a paper-making machine of the character described, a shaking forming section, a supporting shaking standard having a curved load-receiving surface at the upper 15 end thereof, a cooperating sustaining surface upon said shaking forming section, a curved bearing surface at the lower end of said standard, a supporting base member having a bearing surface cooperating with 20 the lower curved surface on the supporting standard, means for effecting movement of this supporting standard to cause shaking

of the forming section, the cooperating bearing surfaces at the upper and lower ends of the standard being coaxial, and adjustable 25 means for controlling side thrust of the forming section.

50. In a paper-making machine of the character described, a shaking forming section, a supporting shaking standard, a 30 curved load-receiving surface upon said standard, a cooperating sustaining surface upon said shaking forming section, means for acting upon the said standard to effect shaking of the forming section, the said 35 surfaces being so cooperatively constructed as to effect substantially rolling motion with respect to each other during shaking of the forming section, and means enclosing the supporting standard for sustaining side 40 thrust during operation.

In testimony whereof I hereto affix my signature.

HERMAN L. KUTTER.

CERTIFICATE OF CORRECTION.

Patent No. 1,662,929.

Granted March 20, 1928, to

HERMAN L. KUTTER.

It is hereby certified that error appears in the printed specification of the above numbered patent requiring correction as follows: Page 5, line 82, after the number 151 insert a comma and strike out the parenthetical mark, and line 121, for the word "from" read "and"; and that the said Letters Patent should be read with these corrections therein that the same may conform to the record of the case in the Patent Office.

Signed and sealed this 1st day of May, A. D. 1928.

(Seal)

M. J. Moore,
Acting Commissioner of Patents.
